VEHICLE SIGNAL LIGHT

James R. Richwine, Lorain, Ohio

Application December 8, 1950, Serial No. 13,330

Term of patent 14 years

(Cl. D48—32)

To all whom it may concern:

Be it known that I, James R. Richwine, a citizen of the United States, residing at Lorain, the county of Lorain, in the State of Ohio, have invented a new, original, and ornamental Design for Vehicle Signal Light, of which the following is a specification, reference being had in the accompanying drawings, forming part hereof.

Figure 1 is a plan view of a vehicle signal light, showing my new design.

Fig. 2 is a front elevational view of the vehicle signal light of Figure 1, and

Figure 3 is an end elevational view of the vehicle signal light of Figures 1 and 2.

The drawings are lined to indicate contrasting colors.

I claim:

The ornamental design for a vehicle signal light, as shown and described.

JAMES R. RICHWINE.
